SINTERING MACHINE

Edward W. Shallock, Chicago, Ill., assignor to
American Ore Reclamation Company, Chicago,
Ill., a corporation of New York

Application August 26, 1943, Serial No. 500,074

8 Claims. (Cl. 198—45)

This invention relates to sintering machines, and has to do with sintering machines of the continuous type.

In sintering machines of the type referred to, a train of pallets is propelled along the upper run of a continuous track, by means of sprocket wheels at the feed end of the machine, the pallets at this end of the upper run of the machine being charged with the material to be sintered, after which the bed or layer of material in the pallets is ignited by a suitable igniting furnace, and the charged pallets then pass above wind boxes by means of which air is drawn downward through the material which is sintered by combustion progressing downward therethrough. The train of pallets is such as to leave a gap between two adjacent pallets at the return bend at the delivery or discharge end of the machine, each pallet as it enters the return bend breaking off the sinter and, when it strikes the preceding pallet, discharging the broken off sinter. The pallets then continue their travel around the return bend at the discharge end and travel downwardly along the inclined lower run of the track to the feed end, at which they are engaged by the sprocket wheels and returned to the upper run of the track. The pallets commonly used in machines of this type are provided with depending end walls and with transversely extending reinforcing ribs, providing means for supporting the grates and for bracing the pallets, these walls and ribs extending transversely of the machine and defining, in effect, troughs or pockets which are open at their top, when the pallets are in their inverted position which they occupy at the lower end of the return bend at the discharge end of the machine, and during their travel along the lower run of the track. When one of the pallets passes from the upper run of the track onto the return bend at the discharge end, it tilts and breaks off the sinter, as above stated, that pallet being then separated a short distance from the next succeeding pallet. The breaking of the sinter results in the production of fine particles of the sintered material, commonly termed fines. A chute, commonly termed a spillage apron, is usually provided beneath the upper portion of the return bend at the discharge end of the machine, for catching the fines and conducting them to a fines bin or other suitable point of discharge. This chute is of necessity spaced an appreciable distance from the pallets and a portion of the fines is discharged at the sides of the chute, and these fines drop downward into the pockets or troughs defined by the reinforcing walls and ribs

of the inverted pallets at or adjacent the lower end of the return bend at the discharge end of the machine. Also, during and immediately after discharge of the sinter from each pallet, sinter fines escape between that pallet and the next preceding pallet, and these fines drop downward, in front of the spillage chute or apron, into the pockets of the inverted pallets at the lower portion of the return bend. The fines are retained in the pockets of the inverted pallets as they travel along the lower run of the track, and as the pallets are returned to substantially upright position at the feed end of the machine, by the sprocket wheels, the fines contained within the troughs or pockets of the pallets are discharged therefrom downward between the sprocket wheels, and the fines thus discharged fall in considerable portion into the troughs of the inverted pallets at and adjacent the lower portions of the sprocket wheels. In addition, fine particles of the sinter adhere to the pallets, particularly the grates thereof, from which they are dislodged and discharged downward into the pockets of the inverted underlying pallets, during travel of the pallets around the return bend at the feed end of the machine. That produces a cumulative effect such that the feed end portion of the machine is subjected to a substantially continuous cloud of fines, these fines frequently being highly abrasive in character. The smaller particles of the fines enter the bearings of the sprocket wheel shaft and of the motor and associated mechanisms, frequently resulting in rapid wear and serious injury thereto. While that objection has been generally recognized in machines of the type referred to, it has heretofore been accepted as a necessary evil and, so far as I am aware, no one has been able to avoid that condition.

My invention is directed to means for avoiding the above referred to objection to machines of the type referred to, with respect to injury to the operating mechanism at the feed end of the machine by the fines discharged from the pallets during their travel about the return bend at that end of the machine. To that end, I provide means for collecting the fines discharged from the pallets as they pass around the feed end return bend of the machine, in a manner effectively to prevent at that bend the more or less continuous downward discharge or shower of fines and resulting damage, such as occurs in sintering machines of ordinary type, above referred to. More specifically, I provide a chute extending between the sprocket wheels at the feed end of the machine and disposed to receive the fines discharged from the

pallets as they reach the upper portion of the return bend, thus avoiding or greatly reducing the downward discharge of the fines from the upper to the lower portion of the sprockets, with the resulting cloud of fines about the operating mechanism and injury to the latter due to entry into the bearings and moving parts of the smaller particles of the fines. This chute is so disposed as to receive and confine the fines discharged thereinto, and the fines thus collected are discharged into a suitable conveyor by means of which they are discharged and delivered to a suitable point remote from the machine, such as the fines bin, where they are collected for use in the sintering operation. Further objects and advantages of my invention will appear from the detailed description.

In the drawings:

Figure 1 is a side view of a continuous type of sintering machine embodying my invention, this machine being broken away and certain parts of the mechanisms at the feed end being omitted for clearness of illustration, certain other parts at the feed end being shown in section;

Figure 2 is a side view of the feed end of the machine on an enlarged scale;

Figure 3 is a transverse vertical sectional view taken substantially on line 3—3 of Figure 2;

Figure 4 is a view in elevation of the fines chute and the fines receiving trough and associated parts, looking toward the feed end of the machine, parts being shown in section and certain other parts being broken away;

Figure 5 is a view in elevation of the fines chute and the fines receiving trough and associated parts as viewed from the side of the machine shown in Figures 1 and 2, certain parts of the machine being shown in section and certain parts being omitted for clearness of illustration; and

Figure 6 is a plan view of the fines receiving trough and the fines chute and associated parts, certain parts being broken away.

I have shown my invention as embodied in a sintering machine of known construction and operation, a brief description of which will suffice. It comprises a suitable frame 10 supporting an endless track having upper and lower runs 11 and 12, respectively, connected at the discharge end of the machine by a return bend 13 and, at the feed end of the machine, by a return bend 14. Pallets 15, of known construction, travel along the track in endwise abutting contact forming a train, except at the return bend. The number of pallets is such that a gap or space 16 is provided between the end pallets of the train at the upper portion of the return bend 13, at the discharge end of the machine, the pallets extending about this bend being in endwise contact. The lower run 12 of the track is inclined downward toward the feed end of the machine, to which the pallets travel by gravity. At the feed end of the machine the pallets are moved around the return bend 14, by means of a pair of sprocket wheels 17 secured on a drive shaft 18, and returned to the upper run 11 of the track, along which they are propelled by the sprocket wheels. The pallets are loaded or charged with the material or the mixture of materials to be sintered by means of a hopper or spout 19, after which the charged pallets pass beneath an ignition furnace 20, by means of which the layer or bed of material in the pallets is ignited at its upper surface. The pallets then travel over wind boxes 21, connected to suitable suction means, in a known manner, by means of which air is drawn

downward through the bed of material on the pallets, sintering the material by downward combustion. When the material in the pallets has been sintered, the pallets pass about the return bend 13, each pallet as it enters the upper portion of this return bend being tilted relative to the next succeeding pallet, this tilting action serving to break off a piece or block of the sinter and, as the pallet travels downward about return bend 13, it strikes the next preceding pallet and the broken off block of sinter is discharged from the pallet. Referring to Figure 1, a pallet 15a is shown in dotted lines entering the upper portion of return bend 13 and tilted relative to the next succeeding pallet. That serves to break off a block of the sinter and, as previously noted, in breaking off this block of sinter, fine particles of sinter or fines are produced. A large portion of these fines drop into a spillage apron or chute a, disposed beneath the upper portion of return bend 13, from which they are conducted by a spout b to a fines bin or other suitable point of discharge. A considerable portion of the fines, however, are discharged beyond the sides of chute a, and these fines drop downward to the lower end portion of the return bend 13. The pallet then continues to travel around return bend 13 until it reaches its full line position at 15b, where it strikes the next preceding pallet, with the result that the piece or block of sinter is discharged from the pallet. When the sinter is discharged from the pallet, as it reaches its position at 15b, sinter fines f are discharged between that pallet and the next preceding pallet and drop to the lower portion of bend 13.

The main drive shaft 18 of the machine is mounted for rotation in suitable bearing blocks mounted in a known manner on frame 10, at the sides thereof, as will be clear from Figure 2. A countershaft 25 is rotatably mounted transversely of frame 10, in bearing blocks suitably mounted thereon, in advance of and parallel with the main drive shaft. A spur pinion 26 is keyed on one end of countershaft 25 and meshes with a spur gear 27 keyed on the corresponding end of shaft 18. A spur gear 28 is keyed on the other end of countershaft 25 and meshes with a spur pinion 29 keyed on shaft 30 of a speed reducing unit 31, of known type suitably mounted adjacent and anchored to frame 10 of the machine. Unit 31 is provided with a drive shaft 32 which may be driven from any suitable source of power, conveniently an electric motor having either a direct driving connection to shaft 32 or a belt and pulley drive thereto. It will be understood that any other suitable or preferred known means may be provided for driving the shaft 18 at proper speed and in proper direction.

The pallets 15 may be of any suitable known construction, but preferably are constructed similarly to the pallet disclosed in my Patent No. 1,722,344, issued July 30, 1929. Each pallet comprises a rectangular frame with side walls 35 connected by end walls 36 and intermediate reinforcing ribs 37 (Figure 3), the ribs and the end walls being connected by an intermediate wall 38 having dovetail recesses or sockets which receive corresponding locking heads 39 depending from the inner ends of grate sections 40 seating on the upper faces of the end walls 36 and the ribs 37. At their outer ends the grate sections 40 receive locking pins 41 disposed at the upper faces thereof, and restraining the grate sections against movement relative to the pallet frame. A side flange 42 is riveted or otherwise suitably secured

to each of the side walls 35, extending upward therefrom a suitable distance such that the pallet provides, in effect, a pan of considerable depth for reception of the bed or layer of material to be sintered. The ribs 37 and end walls 36 of the pallet may be connected by supplemental reenforcing ribs 44. It will be understood that the particular construction of the pallet, so far as the details thereof are concerned, is not of the essence of my invention. It should be noted, however, that all pallets commonly used on continuous type sintering machines are provided with side walls and reenforcing ribs or equivalent elements, corresponding to the side walls 35 and the ribs 37 of the pallet here shown and described, such ribs and walls defining, when the pallet is in an inverted position, pockets or trough-like depressions.

Referring to Figure 1, it will be seen that when the pallets are in inverted position, as shown at the feed end of the machine, at the lower portion of the sprocket wheel 17 there shown, the walls 36 and ribs 37 define upwardly opening pockets or troughs. The fines f_1 dropping from the upper portion of return bend 13 at the discharge end of the machine fall into the troughs or pockets of the inverted pallets at the lower portion of this return bend, and are retained loose in such troughs during travel of the pallets downward along the lower run 12 of the track to the feed end of the machine. During travel of the pallets upward about the return bend 14, the fines are retained in the troughs between the ribs 37 and walls 36 of the pallets, until the pallets reach a position at the upper portion of that return bend. In that connection, it may be noted that the fines are usually rather hard and gritty in character and are not discharged to any considerable extent from between the ribs 37 and walls 36 of the pallet until the pallet reaches a position at the upper portion of the return bend 14.

As previously explained, when the pallets reach the upper portion of the return bend at the feed end of the machine, the loose fines are discharged downward from the pallets, and, in continuous sintering machines of present construction, fall downward between the sprocket wheels into the inverted pallets at the lower portions thereof, the effect being cumulative and the parts at the return bend of the machine, at the feed end thereof, being enclosed in a cloud of the finer particles of the fines, with the objectionable results above referred to with respect to excessive wear of the moving parts of the mechanisms at that end of the machine. I have obviated that objection by providing a fines receiving and collecting chute 45 extending from the upper portion of the return bend 14 at an inclination downward thereof. The chute 45 conveniently is formed of sheet metal, provided at each side with an upwardly extending flange 46, and is supported by means of a U-shaped hanger 47 secured thereto and having upwardly extending arms 48 riveted or otherwise suitably secured to I beams 49 constituting elements of the machine frame 10. The manner in which the chute 45 is supported is shown more clearly in Figure 5, but it will be understood that this chute may be supported in any other suitable manner.

At its upper end chute 45 is of such width as to underlie the pallets 15 for the full interior width of the pallet frame, as will be clear from Figure 3, and as shown in the latter figure the chute 45 decreases in width downward, for a purpose which will be explained presently.

A fines receiving trough 51, conveniently formed

of metal and open at its top, is disposed transversely of frame 10 below and slightly in advance of countershaft 25. This trough is provided, at the upper edge of each side thereof, with an outwardly extending flange 52 the front one of which seats upon a channel bar 53 extending parallel therewith and mounted, by brackets 54, on hold down angle rails 55, secured to frame 10 of the machine in a known manner and disposed above the lower run 12 of the track. A mounting plate 56, welded or otherwise suitably secured to and extending downward from the lower portion of trough 51, at the end thereof adjacent the side of the machine at which the gear wheel 27 and pinion 26 are disposed, is secured to the adjacent hold down rail 55, conveniently by welding. At its other end the trough 51 is closed by a plate 57 (Figure 5) which is extended toward the return bend 14, this plate passing beneath a channel beam 58 of frame 10 and being secured, conveniently by riveting, to an angle bracket 59 riveted or otherwise suitably secured to channel beam 58 and projecting downward therefrom. The trough 51 is thus rigidly supported in position 25 extending transversely of frame 10, though it is to be understood that any other suitable or preferred means may be provided for supporting this trough. The chute 45 is open at its lower end and is there provided with a depending lip 60 (Figures 5 and 6) which extends downward into trough 51 at the inner face of the back wall thereof. Conveniently, the lower portion of chute 45 rests upon the upper flange of channel beam 58, as shown in Figure 5, to which it may be secured in any suitable manner or, if desired, chute 45 may be supported at its lower end on the top of the side wall of the trough 51. It will be seen that the sinter fines discharged into the chute 45, which preferably extends above the main drive shaft 18 of the machine, are collected by this chute and directed thereby into the trough 51. Preferably, I provide means whereby the fines delivered to the trough 51 are continuously discharged therefrom and conducted to a suitable bin or other collection point.

A screw conveyor 62 of known type is rotatably mounted within trough 51 lengthwise thereof, shaft 63 of this screw conveyor being suitably mounted in appropriate bearing sleeves or blocks 50 secured through the end walls of trough 51. The screw of conveyor 62 terminates a short distance from the end of the trough adjacent which the mounting plate 56 is disposed, this end portion of the trough being provided with a downwardly opening discharge collar 64 extending into the flared upper portion 65a of a down spout 65, which may lead to a bin or other suitable point of discharge for collecting the sinter fines. A sprocket wheel 66 is secured on the other end of shaft 63 of the screw conveyor, this sprocket wheel receiving a chain 67 passing about a sprocket wheel 68 secured on countershaft 25. It will be seen that when the sintering machine is in operation, the screw conveyor 62 is continuously driven and serves to move the sinter fines delivered to trough 51 by the chute 45 lengthwise of the trough to the discharge opening defined by collar 64, so that the fines are continuously discharged from the trough and are conveyed by the spout 65 to a fines storage bin or other suitable location, from which these fines may be removed as required for use in the sintering operation or for other purposes.

In most cases the chute 45 is disposed above the shaft 18 since, as previously noted, the fines

are usually gritty and more or less hard in character and are not discharged from the pallets until the latter reach the upper portion of the return bend 14 at the feed end of the machine. There may be cases, however, in which the fines, due to their character or other causes, would be discharged from the pallets when the latter reach a position a short distance above the horizontal plane of the axis of shaft 18. In such cases, the chute 45 may be disposed below shaft 18 instead of above it, the fines then sliding off of the ribs and the walls of the pallets into the chute, to which they are delivered with a minimum drop or fall, reducing to a minimum the fine particles of fines which may tend to be suspended in the air. Briefly, the chute 45 may be disposed either above or below the shaft 18, depending upon conditions, and serves in either case to receive the fines discharged from the pallets as the latter move about the return bend at the feed end of the machine, and to direct these fines to the trough 51 and associated screw conveyor. The particular construction of the chute 45 is not of the essence of my invention, in its broader aspects, nor is the particular arrangement of the trough and the screw for conveying the collected fines to the bin or other suitable point of discharge. My invention comprehends, within its broader aspects, any suitable construction of chute or analogous means for collecting the fines, and any suitable means for conveying the collected fines to an appropriate point or location. It will be understood that changes in construction and arrangement of parts of my invention may be resorted to without departing from the field and scope thereof, and I intend to include all such variations, as fall within the scope of the appended claims, in this application in which the preferred form only of my invention has been disclosed.

I claim:

1. In a sintering machine, an endless track having an upper run and a lower run connected by a discharge end return bend and a feed end return bend, a train of pallets travelling on said track, means for moving the pallets about said feed end return bend from said lower run to said upper run comprising a drive shaft rotatably mounted transversely of said machine and sprocket wheels secured on said shaft, a driven countershaft disposed inwardly of said machine beyond said sprocket wheels and parallel with and having driving connection to said drive shaft, conveyor means driven by said countershaft, and a fines receiving chute mounted at said feed end return bend inclined downwardly and inwardly of said machine extending between said sprocket wheels and disposed between the upper and the lower portions of said feed end return bend with its upper end in proximity to the bottoms of pallets passing thereabout for receiving loose sinter fines discharged from the latter pallets, said chute delivering the fines to said conveyor means.

2. In a sintering machine, an endless track having an upper run and a lower run connected by a discharge end return bend and a feed end return bend, a train of pallets travelling on said track, means for moving the pallets about said feed end return bend from said lower run to said upper run comprising a drive shaft rotatably mounted transversely of said machine and sprocket wheels secured on said shaft, a driven countershaft disposed inwardly of said machine beyond said sprocket wheels and parallel with and having driving connection to said drive shaft, con-

veyor means driven by said countershaft disposed transversely of said machine and inwardly thereof or beyond said sprocket wheels and discharging laterally of said machine, and a fines receiving chute inclined downwardly and inwardly of said machine extending between said sprocket wheels and disposed between the upper and the lower portions of said feed end return bend with its upper end in proximity to the bottoms of pallets passing thereabout for receiving loose sinter fines discharged from the latter pallets, said chute delivering the fines to said conveyor means.

3. In a sintering machine, an endless track having an upper run and a lower run connected by a discharge end return bend and a feed end return bend, a train of pallets travelling on said track, means for moving the pallets about said feed end return bend from said lower run to said upper run comprising a drive shaft rotatably mounted transversely of said machine and sprocket wheels secured on said shaft, a driven countershaft disposed inwardly of said machine beyond said sprocket wheels and parallel with and having driving connection to said drive shaft, a fines receiving trough parallel with said countershaft disposed inwardly of said machine beyond said sprocket wheels and having a discharge outlet, conveyor means operating in said trough driven from said countershaft for moving the fines to said outlet, and a fines receiving chute inclined downwardly and inwardly of said machine extending between said sprocket wheels and disposed between the upper and the lower portions of said feed end return bend with its upper end in proximity to the bottoms of pallets passing thereabout for receiving loose sinter fines discharged from the latter pallets, said chute delivering the fines to said trough.

4. In a sintering machine, an endless track having an upper run and a lower run connected by a discharge end return bend and a feed end return bend, a train of pallets travelling on said track, means for moving the pallets about said feed end return bend from said lower run to said upper run comprising a drive shaft rotatably mounted transversely of said machine and sprocket wheels secured on said shaft, a driven countershaft disposed inwardly of said machine beyond said sprocket wheels and parallel with and having driving connection to said drive shaft, a fines receiving trough parallel with said countershaft disposed inwardly of said machine beyond said sprocket wheels and having a discharge outlet at one side of said machine, conveyor means operating in said trough driven from said countershaft for moving the fines to said outlet, and a fines receiving chute inclined downwardly and inwardly of said machine extending between said sprocket wheels and disposed between the upper and the lower portions of said feed end return bend with its upper end in proximity to the bottoms of pallets passing thereabout for receiving loose sinter fines discharged from the latter pallets, said chute delivering the fines to said trough.

5. In a sintering machine, an endless track having an upper run and a lower run connected by a discharge end return bend and a feed end return bend, a train of pallets travelling on said track, means for moving the pallets about said feed end return bend from said lower run to said upper run comprising a drive shaft rotatably mounted transversely of said machine and sprocket wheels secured on said shaft, a driven countershaft disposed inwardly of said machine beyond said sprocket wheels and parallel with and

and having driving connection to said drive shaft, a fines receiving trough parallel with said countershaft disposed inwardly of said machine beyond said sprocket wheels and having a discharge outlet at one side of said machine, conveyor means operating in said trough for moving the fines to said outlet, said conveyor means having a drive shaft parallel with and driven by said countershaft, and a fines receiving chute inclined downwardly and inwardly of said machine extending between said sprocket wheels and disposed between the upper and the lower portions of said feed end return bend with its upper end in proximity to the bottoms of pallets passing thereabout for receiving loose sinter fines discharged from the latter pallets, said chute delivering the fines to said trough.

6. In a sintering machine, an endless track having an upper run and a lower run connected by a discharge end return bend and a feed end return bend, a train of pallets travelling on said track, means for moving the pallets about said feed end return bend from said lower run to said upper run comprising a drive shaft rotatably mounted transversely of said machine and sprocket wheels secured on said shaft, a driven countershaft disposed inwardly of said machine beyond said sprocket wheels and parallel with and having driving connection to said drive shaft, a fines receiving trough parallel with said countershaft disposed inwardly of said machine beyond said sprocket wheels and having a discharge outlet at one side of said machine, a conveyor screw operating in said trough and driven by said countershaft for moving the fines to said outlet, and a fines receiving chute inclined downwardly and inwardly of said machine extending between said sprocket wheels and disposed between the upper and the lower portions of said feed end return bend with its upper end in proximity to the bottoms of pallets passing thereabout for receiving loose sinter fines discharged from the latter pallets, said chute delivering the fines to said trough.

7. In a sintering machine, an endless track

having an upper run and a lower run connected by a discharge end return bend and a feed end return bend, a train of pallets travelling on said track, the pallets adjacent the lower end of the discharge end return bend being inverted and underlying the pallets adjacent the upper end of the latter bend and disposed to receive therefrom loose sinter fines liberated incident to discharge of the sinter, said pallets comprising elements defining upwardly opening pockets when the pallets are in inverted position effective for receiving and retaining the loose sinter fines, means for moving the pallets about said feed end return bend from said lower run to said upper run, and means at the feed end return bend between the upper and lower portions thereof extending into proximity to the bottoms of pallets travelling thereabout and disposed to receive loose sinter fines discharged by gravity from the pockets of such pallets.

8. In a sinter machine, an endless track having an upper run and a lower run connected by a discharge end return bend and a feed end return bend, a train of pallets travelling on said track, the pallets adjacent the lower end of the discharge end return bend being inverted and underlying the pallets adjacent the upper end of the latter bend and disposed to receive therefrom loose sinter fines liberated incident to discharge of the sinter, said pallets comprising elements defining upwardly opening pockets when the pallets are in inverted position effective for receiving and retaining the loose sinter fines, means for moving the pallets about said feed end return bend from said lower run to said upper run, and a chute between the upper and lower portions of said feed end return bend inclined downward and inward of said machine lengthwise thereof extending into proximity to the bottoms of pallets travelling about said last mentioned bend and disposed to receive loose sinter fines discharged by gravity from the pockets of such pallets.

EDWARD W. SHALLOCK.
